Primary Examiner — Barbara Fox*Assistant Examiner* — Mehri F Bajoul(74) *Attorney, Agent, or Firm* — Chan Hubbard PLLC;
 Keala Chan(57) **CLAIM**

The ornamental design for a catching game, as shown and described.

DESCRIPTION

FIG. 1 is a front perspective view of a catching game, showing my new design;

FIG. 2 is a top elevational view thereof;

FIG. 3 is a bottom elevational view thereof;

FIG. 4 is a rear elevational view thereof;

FIG. 5 is a front elevational view thereof;

FIG. 6 is a left elevational view thereof; and,

FIG. 7 is a right elevational view thereof.

The broken lines shown in the drawings depict portions of the catching game that form no part of the claimed design.
